UNITED STATES PATENT OFFICE

2,549,279

VAPORIZING TYPE LIQUID FUEL BURNER

Charles Yvelin, Vernon, France

Application February 20, 1948, Serial No. 9,649
In France November 28, 1945Section 1, Public Law 690, August 8, 1946
Patent expires November 28, 1965

2 Claims. (Cl. 158—91)

1

My invention has for its object a liquid fuel burner of the type including a chamber with vertical side walls and downwardly sloping pipes mounted in said walls and adapted to feed primary air of combustion into the burner through the walls thereof together with further means for feeding the secondary air and the fuel oil into the burner.

The object of my invention is to provide for the arrangement of the primary air feeding pipes in side by side relationship in a manner such that they lie under different angles with reference to horizontality and produce thus jets converging substantially towards the central part of the burner chamber. As a consequence of this arrangement, the sprays of primary air while angularly shifted with reference to one another, crowd against each other towards the center of the pot so as to provide a better splitting of the layer of oil at the bottom of the pot.

My invention has thus for its further object a pot wherein the mixture is commingled and atomized perfectly, the mixing being operated energetically by the jets of primary air arriving along different angular directions.

In the accompanying drawings that show an embodiment of a burner in accordance with the invention:

Fig. 1 is a longitudinal view taken partly in section through the line I—I of Fig. 3;

Fig. 2 is a lateral view taken on the delivery side of the fuel oil.

Fig. 3 is a lateral view on the side opposite to the oil delivery.

Fig. 4 is a section through 4—4 of Fig. 2 passing through pipe C.

Fig. 5 is a section through line 5—5 of Fig. 3 passing through pipe D.

Fig. 6 is a section through line 6—6 of Fig. 2 passing through pipe E.

The burner is made up of a metal pot of rectangular shape with a bottom wall or atomising plate or base plate 1 and side walls 2 and 3 constituting faces or supports for nozzles, and connected by two other, longitudinal walls 4—5. This pot is packed round with suitable lagging the object of which is to keep the burner at red heat so as to ensure the combustion of fumes and any residues and thus increase its efficiency. It is capped by two sloping thick cheek plates for heat storage 7—8 (Fig. 1) fitted together by two lateral inclined plates 9—10 provided with apertures 11 and carrying a nozzle 12 for the exit of the flame in connection with the customary heating means.

2

The front wall 2 includes a series of pipes A—C—C—E—E (Fig. 2). The feed pipe Y, connected to the oil tank (not shown) is inserted in the discharge pipe A at the point a (Fig. 1).

The rear wall 3 (Fig. 3) is provided with a series of pipes B—D—D. The pipe B is in communication, through an aperture b (Fig. 1) cut in its wall, with a tube M opening into the waste-oil cup m into which the pipe 2 dips at a small distance from the bottom of the cup, said pipe being also linked up with the oil feed (not shown). It must be emphasized that the axes of all the pipes A—B—C—D—E intersect at different angles the base plate 1 of the pot. Thus A forms an angle of 18°, B of 12°, C of 25°, D of 12° (Fig. 5) and E of 25° (Fig. 6) like C. In this way, the sprays, while operating one under the other, end by crowding against each other due to their varying slope.

The burner operated in the following manner: the pipe A receives the oil, drop by drop, through the small aperture a, coming through the feed pipe Y; the oil spreads out in front of the discharge of the pipe A. For starting the burner, the oil is lit by hand, then, after a few minutes, the feed is increased and when the burner is hot enough, the feed delivery is adjusted.

When the burner is running on low fire, the fuel oil settles at the lower part of the discharge end of pipe A, the pipes E head the air for combustion on to the residual material spread out round this pipe A, causing the burning of the oil thus collected; in this way is avoided any accumulation of cinders that may occur if the burner runs for too long a time on slow fire. When the burner is hot enough and after the volume of feed is increased, there is obtained a strong suction through the air pipes, the oil follows the upper portion of pipe A and is thrown into the middle of the pot bottom.

The air from the pipes A—B splits up the layer of oil deposited on the base plate and fills up, together with the light fumes of combustion, the middle portion of the burner from the base plate to the discharge end of nozzle 12; the upper portion of the burner, tapering towards the nozzle, restricts the output end of the flame and constitutes an atomising chamber between the middle portion and the walls of the burner. The fumes produced in these portions are mixed vigorously by the primary air through tubes C—D due to the varying slope of their axes with reference to the base plate. Combustion is finished off by meeting the secondary air that has been

warmed up by going through the apertures 11 of the perforated plates 9-10 that are heated by the thick cheek plates 7-8.

The flame issuing from the burner is free of smoke and has a very high thermal efficiency, while the burner never requires cleaning. If it happens to go out from some cause or other, the layer of fuel gets thicker and rises up to the aperture b, flows along the tube M, fills the waste-oil cup m and chokes the air pipe Z from the oil tank, and this prevents air at atmospheric pressure from acting on the oil contained in the tank; the latter is closed hermetically with a plug. Emptying of the waste-oil cup m allows the starting up of the burner as well as the oil feed arrangements.

What I claim is:

1. A burner for operating on fuel oil for feeding hot gases to external heating means comprising a metal pot with two opposite substantially vertical walls, at least two series of downwardly sloping pipes mounted in said walls and adapted to feed primary air of combustion into the pot through said walls and arranged side by side under different angles with reference to horizontal-
ity for producing jets converging substantially to-
wards the middle of the bottom of the pot, means
for feeding secondary air into the pot and means
for feeding fuel oil into the end of at least one
of the sloping pipes through the wall thereof.

2. In a liquid fuel burner including a chamber
with vertical side walls, downwardly sloping pipes

mounted in said walls and adapted to feed pri-
mary air of combustion into the burner through
the walls thereof, and arranged side by side under
different angles with reference to horizontality
for producing jets converging substantially to-
wards the central part of the burner chamber,
means for feeding secondary air into the burner
and means for feeding fuel oil into the end of at
least one of the sloping pipes slightly ahead of the
point of opening thereof into the burner chamber.

CHARLES YVELIN.
